APPARATUS FOR REGROOVING SUGAR
MILL ROLLS

Charles A. Wainwright, Raceland, La.

Application February 8, 1946, Serial No. 646,279

2 Claims. (Cl. 90—15)

1

This invention relates to apparatus for regrooving, or cutting new grooves, in sugar mill rolls.

The grooves referred to are the series of parallel grooves which extend across the surface of the roll, each consisting of oppositely inclined portions symmetrical with respect to the center circumference of the roll, and which meet at an obtuse angle at the center circumference. The grooves are cut with an abrupt shoulder facing the direction of rotation of the roll, forming teeth in the ridges between the circumferential juice ducts, which teeth engage the cut cane and feed it between cooperating rolls.

In use, the teeth become blunted, chipped and otherwise scarified, so that from time to time it becomes necessary to regroove the rolls to restore the teeth. All sugar mills have a bench with spaced open bearings upon which a dismantled roll is set, for the purpose of regrooving. Generally, regrooving is done by hand with a chisel. This is a time-consuming operation and the job is far from perfect, for it is difficult to maintain the angle of the groove constant, and the chisel breaks the point of the tooth and swells the metal into the annular juice ducts, making a poor fit with the cooperating roll, and causing breakage of the scrapers and return plates in some cases. Some foundries and machine shops which manufacture rolls still cut the grooves manually.

The general object of the present invention is to provide apparatus for regrooving or cutting new grooves, automatically by a milling cutter, which cuts at a constant angle, leaving a clean cut, forming a smooth tooth without any broken or swollen places in the adjacent annular juice ducts, thereby providing a better feeding condition to the sugar mill train of rolls, without hazard of breaking the scrapers or return plates.

A more specific object of the invention is to provide apparatus which can be used in combination with the bench above referred to, comprising a traveling slide rest carrying a milling cutter movable parallel to the axis of the roll, means for slowly rotating the sugar roll, and means for driving both the slide rest and roll rotating means in synchronized relation so that the angle of groove is the resultant of the relative rates of movement of the slide rest and the roll.

Other objects of the invention will appear as the following description of a preferred and practical embodiment thereof proceeds.

In the drawings:

Figure 1 is a plan view of apparatus embodying the principles of the invention, shown in operative relation to a sugar mill;

2

Figure 2 is a side elevation of the apparatus, partly in section, taken along the line 2—2 of Figure 1;

Figure 3 is an end elevation of what is shown in Figure 1;

Figure 4 is a section taken along the line 4—4 of Figure 2;

Figure 5 is a section taken along the line 5—5 of Figure 2, showing the tumbler gear;

10 Figure 6 is a side elevation of a portion of the sugar roll, showing one of the grooves;

Figure 7 is a perspective view of the slide rest and milling cutter unit.

Referring now in detail to the several figures, 15 the numeral 1 represents a platform on which are mounted the longitudinally spaced open bearing supports 2, carrying the roller bearings 3. The dismantled sugar roll is shown at 4 in Figure 1, having cylindrical journals 5 and 6, extending

20 from the opposite ends, resting upon the opposite bearings 3, so that the roll can be turned on said bearings. The journal 5 has a reduced end 7, on which is keyed the worm gear 8, by which the roll 4 is driven in the mill.

25 The above means for supporting the dismantled roll, for doing repair work upon it, is conventional.

The grooving apparatus comprises a slide rest traveling parallel to the axis of the roll carrying

30 a milling cutter for making the groove, means for rotating the roll while the slide rest is traveling, for giving the desired angle of inclination to the groove, a motor, and driving connections from the motor to the slide rest, roll rotating

35 means and cutter.

The means for rotating the roll 4 is shown in Figure 3, and consists of a shaft 9 journaled in bearings 10, 11 and 12, carrying a freely revolute worm 35, abutting a collar 13, fixed on the

40 shaft 9. A clutch 15 is splined on the shaft 9 adjacent the worm, engageable with the clutch face 14 on the adjacent end of the worm by means of which the worm is driven when the clutch is engaged. The shaft 9 carries a driving sprocket 16.

45 Said shaft is mounted perpendicular to the axis of the roll with the worm directly beneath the axis of the roll in position to be engaged by the worm wheel 8 when the roll is placed upon the bench.

50 The lathe which carries the milling cutter comprises a pair of spaced vertical end plates 17 and 18, which rest upon the platform 1. Between these, a horizontal track member 19 extends, composed of the spaced L-shaped beams

55 20, having out-turned flanges 21 at the top, and

forming a channel 22 between them. The beams 20 are secured to brackets 23, fixed to the end plates. A shaft 24 extends horizontally through the channel 22, formed as a propulsion screw 27, throughout the length of said channel, said shaft being journaled in the end plates and extending therebeyond. A carriage 25 is slidably mounted on the track member 19, and has a longitudinal rib 26 on its under side extending into said channel, with a threaded bore engaging the screw 27, by which interconnection the carriage 25 can be made to travel the length of the track member 19, in either direction, depending upon the direction of rotation of the propulsion screw 27.

The carriage is provided with a dovetail guideway 28, perpendicular to the direction of travel of the carriage, forming a track for a slide rest 29, which comprises a plate 30, resting upon the carriage, having fixed thereto a dovetail slide 34, fitting within the guideway 28. The carriage is provided with an upwardly extending front wall 31, having a bearing aperture in alignment with the guideway 28, in which is journaled a screw shaft 33, extending through said guideway and through a threaded bore in the slide 34. The screw is secured against endwise movement with respect to the wall 31, and has a crank at its opposite end for rotating it to move the slide rest forward and backward relative to said carriage.

On the plate 30 of the slide rest is mounted the milling cutter unit, which consists of a horizontal base 36, having a vertical front wall 37, through the central portion of which the shaft 38 of the milling cutter 39 extends, said shaft being journaled in bearings in the ends of the housing 49, fixed to said base. On each side of the milling cutter shaft the front wall 37 is provided with projecting pins 41, on which pairs of idler sprockets 42 are journaled. The milling cutter shaft 38 also carries a pair of sprockets 43 between the cutter and front wall in the vertical planes of the sprockets 42, for driving the milling cutter.

Figure 1 shows that there is a horizontal shaft 44 above the track member 19 at one end, journaled in bearings 45, fixed to the end plate 17, and that there is a horizontal shaft 46 similarly positioned at the opposite end of the track member carried in bearings 47, fixed to the end plate 18. The shaft 46 extends backward a sufficient distance to receive a sprocket 48, chain driven from the motor 49. The forward ends of shafts 44 and 46 carry pairs of sprockets 50 at the same vertical planes as the sprockets 42. Beneath the track member 19, at the middle, a stub shaft 51 is journaled, carrying a pair of sprockets 52 in the vertical planes of the sprockets 43. Double chains 53 are arranged in triangular formation, as shown, about the sprockets 43, 42, 50 and 52, the sprockets 42 defining a deep bight in the chain about the sprockets 43 which drive the milling cutter.

The shaft 24 which carries the screw 27 for propelling the slide rest carriage has a double faced clutch 54 splinably mounted upon its extended righthand end portion, as viewed in Figure 1, adapted to be selectively coupled with either of the bevel gears 55 or 56, rotatably but nonslidingly mounted upon the shaft 24. Said gears are in mesh with the opposite sides of a bevel gear 57 on a shaft 58, having a sprocket 59, chain connected to a sprocket 60 on the drive shaft 46. By operating the clutch, reversal of movement of the screw 27 is obtained. The clutch also has a neutral position, freeing the

screw from its driving connection so that it can be quickly turned by the hand wheel 61 mounted at the extreme end of the shaft 24.

The lefthand end of the screw shaft 24, as viewed in Figure 1, carries a gear 62, which through selectively engageable reversing gears 63 and 64, drives a gear 65 on a horizontal shaft 66, having a bearing in the end plate 17 and a bearing fixed to the platform. The outer end of this shaft carries a sprocket 67, chain connected to a sprocket 68, which drives a shaft 69, supported in bearings in the top of the end plate 17. This last mentioned shaft carries a worm 70. This worm meshes with a worm wheel 71 on the shaft 72, mounted in bearings at the top of the end plate 17, having a sprocket 73 chain connected to the sprocket 16 on the shaft 9, which turns the roll 4.

There is considerable reduction in gear ratio in the driving train between the screw 27 and the worm wheel 8 on the end of the roll 4, so that the roll turns very slowly compared with the longitudinal traverse of the milling cutter, making a groove at an acute angle to the longitudinal dimension of the roll.

As clearly shown in Figure 3, the axis of rotation of the milling cutter is in a plane parallel to, but below the horizontal axial plane of the roll 4, so that the recess or groove made by the milling cutter is deep and abrupt at its upper end but feathers out to the surface of the roll at its lower end.

The intermeshing gears 63 and 64 are journaled on pins carried by a tumbler frame 74, which is pivoted about the shaft 66. The tumbler is tiltable by means of the hand lever 75 to bring either gear 63 or gear 64 into mesh with the driving gear 62. The lever 75 is engageable with teeth on the quadrant rack 76 to lock either of said gears in mesh with the driving gear. By this means, direction of rotation of the roll 4 may be reversed when the milling cutter has reached the middle of the groove, for reversing the obliquity of the groove.

To operate, the roll 4 is placed upon the bearings 3, with the worm wheel 8 meshing with the worm 35. The worm 35 is declutched from the shaft 9. This disengages the entire reclutching apparatus except the worm, from the roll 4, so that the latter can be rotated by hand to bring the groove to be redressed in alignment with the milling cutter.

The clutch 54 is placed in neutral position and the hand wheel 61 turned to rapidly rotate the screw 27 and bring the carriage and slide rest quickly into end position adjacent the end plate 18. The roll is now turned manually to register the end of the groove with the milling cutter. The clutch 54 is then engaged with the worm 35 and the clutch 54 engaged with the bevel gear 55, which rotates the screw 27 in a forward direction. The tumbler gear is put into engagement with the gear 62.

The motor is now started. The carriage 25 travels from right to left; the milling cutter rotates; the roll turns slowly and the groove is progressively cut obliquely as the milling cutter proceeds toward the center of the roll. When the center is reached, the tumbler frame is reversed to bring the gear 64 in mesh with the gear 62. This reverses the direction of rotation of the roll so that as the milling cutter continues to travel across the surface of the roll its path on the roll will be oblique in the opposite direction.

The milling cutter may be made to make a re-

turn cut in the same groove by shifting the clutch 54 to engage the bevel gear 56, thus reversing the direction of rotation of the screw 27, which causes the carriage to travel back from left to right. In the execution of this return cut the tumbler frame must be shifted at the middle point in the groove.

The depth of the cut is regulated by turning the crank of the screw shaft 33, which advances the milling cutter depthwise into the groove. The chains 53 have enough slack to permit the movement of the sprockets 43 in a forward direction with the milling cutter.

When it is desired to turn the roll 4 to the next groove, the motor is stopped, the clutch 15 is disengaged from the worm 35, and the sequence of operations above described is repeated.

By changing the sprocket 16 to one of different size, and altering the length of the chain connections to said sprocket accordingly, a different speed ratio between the roll 4 and carriage 25 may be obtained, for cutting grooves of different obliqueness.

While I have in the above disclosure described what I believe to be a preferred and practical embodiment of the invention, it will be understood to those skilled in the art that the specific details of construction and arrangement of parts as described are by way of illustration and not to be construed as limiting the scope of the invention.

What I claim as my invention is:

1. Apparatus for grooving sugar mill rolls comprising a supporting frame including a longitudinal guide, a carriage slideable along said guide, a propulsion screw parallel to said guide threadedly engaging said carriage for moving the latter along said guide, a milling cutter on said carriage, a sprocket on the shaft of said cutter for driving said cutter, a pair of sprockets carried by said frame adjacent the ends of said guide, said milling cutter sprocket and said pair of sprockets being in a common plane, a slack chain passing about said pair of sprockets and said milling cut-

ter sprocket, a pair of idler sprockets on said carriage at opposite sides of said milling cutter sprocket, engaging said chain to dispose the slack in said chain in an extensive arc about said milling cutter sprocket, and means for driving said screw and chain.

2. Apparatus for regrooving a sugar mill roll having a gear at one end and revolvably supported on a horizontal axis, comprising a frame including a guide extending transversely of said roll, a carriage slideable along said guide, a screw shaft having a threaded portion extending parallel to said guide threadedly engaging said carriage for moving the latter along said guide, a milling cutter on said carriage engageable with the surface of said roll having a shaft in a plane parallel to the axis of said roll but offset therefrom, a motor, driving connections from said motor to said screw shaft and said milling cutter, the driving connections to said screw shaft including reversing connections having a neutral position in which said screw shaft is free from the motor drive, a hand wheel on said screw shaft, a worm meshing with the gear on said roll, a driving connection from said screw shaft to said worm, said last named driving connection including reversing mechanism for changing the direction of rotation of said roll, and a clutch for releasing said worm from said driving mechanism.
